SHEPHERD S. WOODCOCK, OF SOMERVILLE, MASSACHUSETTS.

Letters Patent No. 89,109, dated April 20, 1869.

IMPROVEMENT IN PENCIL-SHARPENERS.

The Schedule referred to in these Letters Patent and making part of the same.

To all whom it may concern:

Be it known that I, SHEPHERD S. Woodcock, of Somerville, in the county of Middlesex, and State of Massachusetts, have invented an Improved Pencil-Sharpener, of which the following is a full, clear, and exact description, reference being had to the accompanying drawings, making part of this specification, in which—

Figure 1 is a plan of my improved pencil-sharpener.

Figure 2 is a front elevation of the same.

Figure 3 is an end elevation of the same.

This invention has for its object to produce a pencil-sharpener, which will perform its work rapidly, and leave the pencil with a perfect point, which is not liable to be broken during the operation of sharpening, and consists in a machine, in which the pencil is rotated and fed up, at the desired angle, into contact with a revolving wheel, having its periphery covered with sand-paper, emery-cloth, or other cutting-substance.

To enable others skilled in the art to understand and use my invention, I will proceed to describe the manner in which I have carried it out.

In the said drawings—

A represents the base, or stand, from which rise the posts, or standards, b, in which revolves a horizontal shaft, B, to one end of which is secured a wheel, C, the periphery of which is covered with sand-paper, emery-cloth, or other gritty, or cutting-substance.

D is an elastic band, or belt, which passes around a pulley on the shaft B, or around the shaft itself, and thence passes over the pencil E, which is thus rotated, as the wheel C is revolved, by means of the knob, or handle d.

The pencil E is supported in the required position by means of guides, or holders, e f, projecting up from the stand A, each being provided with an eye of such

diameter as to admit the pencil, and allow of its being freely rotated therein by the band D.

The guide e is braced by a rod, 4, and its eye, 5, is bent or curved so as to resemble a screw-thread, as seen in figs. 1 and 2, so that, as the pencil is revolved in one direction, it will be advanced, or fed forward, and its point retained in contact with the periphery of the wheel C, by which it is cut, or ground down rapidly as required, a guide-rest, g, projecting up from the stand A, serving to press the point of the pencil against the wheel C, and also prevent it from advancing too rapidly.

If preferred, the eyes of both of the holders, e and f, may be made in the form of a screw-thread, and the guide e may be adjusted, by means of the rod 4 and screw 6, so as to vary the angle at which the point of the pencil is presented to the grinding-wheel, thus rendering the point more or less acute, as occasion may require.

The above-described machine is of simple construction, and performs its work in a perfect and rapid manner, while the point of the pencil is not liable to be broken, an event of frequent occurrence where the ordinary pencil-sharpener, now in general use, are employed.

Claim.

What I claim as my invention, and desire to secure by Letters Patent, is—

The within-described pencil-sharpener, consisting, essentially, of the wheel C, with its shaft B, the belt D, guides, or holders e f, and guide-rest g, all combined and operating substantially as set forth.

S. S. WOODCOCK.
